UNITED STATES PATENT OFFICE.

PAUL R. HAHNEMANN, OF NEWARK, NEW JERSEY, ASSIGNOR OF ONE-HALF TO EDMUND W. ZEH, OF NEWARK, NEW JERSEY.

SHEET-METAL HOLLOW-WARE DRAWING-PRESS.

No. 833,716.

Specification of Letters Patent.

Patented Oct. 16, 1906.

Application filed February 18, 1906. Serial No. 301,777.

To all whom it may concern:

Be it known that I, PAUL R. HAHNEMANN, a subject of the German Emperor, and a resident of Newark, in the county of Essex and State of New Jersey, have invented a new and useful Sheet-Metal Hollow-Ware Drawing-Press, of which the following is a specification.

My invention relates to a sheet-metal hollow-ware drawing-press, with the object in view of providing simple and effective means for holding the sheet securely clamped and for operating the plunger while the sheet is so clamped.

A practical embodiment of my invention is represented in the accompanying drawings, in which—

Figure 1 is a view of the press in side elevation. Fig. 2 is a transverse vertical central section of the same. Fig. 3 is a horizontal section in the plane of the line A A of Fig. 2. Fig. 4 is a horizontal section in the plane of the line B B of Fig. 2, and Figs. 5, 6, and 7 are diagrammatical views for illustrating the action of the respective cams on the arms which control the toggle-levers and the eccentric which controls the plunger.

The press-frame may conveniently comprise a pedestal portion 1, on which the hollow die 2 is supported. Uprights 3 and 4 extend upwardly from the pedestal at opposite ends thereon for supporting the working parts of the press, the said uprights being connected at the top by an arched bar 5. The plunger-operating shaft 6 is mounted in suitable bearings in the uprights 3 and 4 and is provided intermediate of the uprights with a crank portion 7, to which the pitman 8 is connected at its upper end, the opposite end of the pitman being connected to the upper end of a slide 9, (see Fig. 2,) the lower end of said slide being connected to the plunger 10.

The slide 9 (see Fig. 4) is provided with tapered ways 11 and 12, which slide, respectively, in grooves 13 14, formed in the opposite walls of a guide-block 15, set between the uprights 3 and 4 and itself constructed to slide up and down in ways 16 17 on the inner faces of the uprights. To the lower end of the guide-block 15 the clamping-jaw 18 is secured, the lower end of said clamping-jaw 18 being arranged to coact with the upper end of the die-block 2 to hold a sheet 19 firmly between them while acted upon by the plun-

ger passing downwardly through the clamping-jaw 18 into contact with the sheet. The upper end of the slide 9 is provided with a rounded socket 20 for receiving the lower end of the pitman, and the latter is held therein by means of a cross-pin 21. The pitman is conveniently made in two parts, male and female, in order to adjust its length, the male part (denoted by 22) being screw-threaded into the female part 8 and held in displacement by means of a set-screw 23. On the opposite ends of the shaft 6, exterior to the uprights 3 and 4, I mount spur-wheels 24 25 and impart motion to these from a drive-shaft 26, mounted at one side of the frame and driven from a suitable source of power. (Not shown.) This drive-shaft 26 I provide with drive-pinions 27 28, the former for engaging the wheel 24 and the latter for engaging the wheel 25. While it is obvious that one of these pinions would drive both wheels 24 25, secured to the common shaft 6, I prefer for the purpose of distributing strain to apply power to both simultaneously by means of the pinions in engagement with each. These spur-wheels 24 25 are, in effect, master-wheels, and while they serve to impart a rotary motion to the shaft 6 for operating the plunger to draw the metal they also control the clamping of the sheet to securely hold it while it is being operated upon by the plunger, and it is to this feature of the invention that particular attention is called.

Two rock-shafts (denoted, respectively, by 29 and 30) are mounted in extended parts of the uprights 3 and 4 near their upper ends, and each is provided with a pair of arms, the members of the arms on the rock-shaft 29 being denoted by 31 32 and those on the shaft 30 by 33 34. These arms are bifurcated and have pivoted between them the upper ends of links for operating the clamp 18.

The links connected with the arms 31 32 are denoted by 35 36 and those connected with the arms 33 34 by 37 38. The links 35 36 are connected at their lower ends with one side of a skeleton frame 39, and the links 37 and 38 are connected at their lower ends to the opposite side of the said frame. The frame 39 is connected to the sliding block 15 by screws 40—in the present instance four in number—which serve to adjust the frame 39, and hence the links, with respect to the sliding block 15, which carries the clamping-jaw

18. Each arm 31 32 33 34 and its respective link 35 36 37 38 form a toggle-lever, two of which are operated by the rock-shaft 29 and two by the rock-shaft 30, for moving the 5 clamping-jaw 18 into clamping relation with respect to the die 2 and lifting it away from the same to release the work.

The shafts 29 30 are rocked by cams on the faces of the master-wheels 24 25, and for convenience in describing the construction and operation of this shaft-actuating mechanism the ends of the shafts 29 and 30 toward the master-wheel 24 will be considered right and the ends toward the master-wheel 25 left. 15 The right end of the shaft 29 is provided with a crank 41, which when the clamping-jaw 18 is in its retracting position, as shown in Fig. 2, occupies a substantially upright position, and the same shaft is provided on its left end 20 with a crank 42, which occupies a position radially at an angle to the shaft 41, preferably an angle of about ninety degrees. The rock-shaft 30 is provided on its right end with a crank 43, which under the same condition 25 of the clamping-jaw 18 as stated above occupies a position substantially horizontal, and the same shaft is provided on its left end with a crank 44, which occupies a position at an angle to the crank 43, preferably an angle 30 of ninety degrees, and extends downwardly from the shaft when the clamping-jaw is in the position shown. The master-wheel 24 is provided on its face with a cam-groove consisting of a portion 45 concentric with the 35 axis of the wheel and with a portion 46 eccentric thereto, the groove being of sufficient size to receive rollers on the wrist-pins of the cranks 41 and 43 on the right ends of the shafts 29 30. The master-wheel 25 is provided on its face with a cam-groove consisting of a concentric portion 47 and an eccentric portion 48, the shape of this groove being shown in dotted lines, Figs. 5 and 6, and its position in Fig. 3, where the antifriction-rollers 45 on the wrist-pin of the crank 44 are just leaving the end of the concentric portion 47 of the said groove. This groove, composed of the parts 47 and 48, is intended to receive antifriction-rollers on the wrist-pins of the 50 cranks 42 44.

In operation, assuming the plunger to be in its retracted position and the plate-holding jaw also raised from the plate, as shown in Figs. 1 and 2 of the drawings, if now the plate be put in position on the die and the press set in operation the master-wheels will be rotated in the direction indicated by the arrow. (See Fig. 5.) The crank 43 on the rock-shaft 30 has just entered the eccentric portion 46 of the cam-groove on the master-wheel 24, and the crank 41 on the rock-shaft 29 is just escaping from the concentric portion of the same groove. At this same moment the crank 42 on the rock-shaft 29 is entering the eccentric portion of the cam on the

master-wheel 25, as clearly indicated in dotted lines, Fig. 5, while the crank 44 on the rock-shaft 40 is just escaping from the concentric portion of the cam on the said master-wheel 25. As these master-wheels continue 70 to revolve in the same direction the crank 43 will be forced downwardly by the eccentric portion of the cam on the master-wheel 24 into the position shown in Fig. 6, straightening the toggle-levers connected with the 75 rock-shaft 30, and at the same time the crank 42 will be forced upwardly by the cam on the master-wheel 25 into the position shown in Fig. 6, rocking the shaft 29 in the direction to straighten the toggle-levers connected with it, thus forcing the clamping-jaw 18 downwardly into clamping position on the plate 19. The swinging of the crank 43 on the right end of the rock-shaft 30 and the swinging of the crank 42 on the left end 80 of the rock-shaft 29 will at the same time swing the crank 44 on the left end of the rock-shaft 30 into the position shown in dotted lines, Fig. 6, and the crank 41 on the right end of the rock-shaft 29 into the position 85 shown in heavy lines, Fig. 6. The rock-shafts 29 30 will be held in this position while the respective cranks engaged with the cam-grooves on the master-wheels are traversing the concentric portion of the said 90 grooves—in the present instance about a quarter-revolution. As soon as this delay has taken place the cam-groove on the master-wheel 24 will have reached a position where its eccentric portion will engage the crank 41 95 on the right end of the rock-shaft 29, while the cam-groove on the master-wheel 25 will have reached a position such that its eccentric portion will at the same time engage the crank 44 on the left end of the rock-shaft 30, 100 and the further revolution of the master-wheels will simultaneously rock the rock-shafts 29 and 30 in the reverse direction, 105 throwing the parts again into the position shown in diagram Fig. 5, with the clamping-jaw lifted from the plate, and after this jaw is lifted there will be a dwell while the cranks are traversing the concentric portions of the respective grooves, during which time the blank which has been operated upon may be 110 removed and another plate placed in position. The relation between the action of the clamping-jaw 18 and the action of the plunger 10 is such that the plunger will begin to act immediately after the clamping-jaw has 115 been thrown into clamping relation on the plate and will continue to act during the interval while the plate is held by the clamping-jaw 18 and will then gradually recede from 120 its position, following the release and upward movement of the clamping-jaw. These 125 relative movements of the clamping-jaw and drawing-plunger are represented in Fig. 7, the heavier line 49 indicating the motion of the clamping-jaw, while the lighter line 50 130

indicates the motion of the plunger. It will be observed that the clamping-jaw first reaches its lowermost position—viz., the position where it clamps the plate—and that it is closely followed by the plunger, which continues on down to the depth to which the plate is to be drawn, while the clamping-jaw occupies the constant position shown by the horizontal portion of the line 49 and that the upward motion of the clamping-jaw then takes place quite rapidly, reaching its retracted position some time before the plunger reaches its retracted position, thereby giving opportunity to manipulate the plate, which may be lifted, together with the plunger. The structure provides for operating simultaneously upon the right end of one rock-shaft and left end of another to advance the clamping-jaw and then in turn operate upon the left end of one shaft and right end of the other to retract the clamping-jaw, a cam acting alternately upon one shaft and then upon another at one end of each shaft and another cam alternately acting upon the shafts at their opposite ends.

It is obvious that changes might be resorted to in the form and arrangement of the parts without departing from the spirit and scope of my invention. Hence I do not wish to limit myself strictly to the structure herein shown and described; but

What I claim is—

1. A drawing-press comprising suitable means for drawing the metal and means for holding the plate to be drawn, said holding means comprising toggle-levers, shafts for operating the toggle-levers and cams at the opposite ends of the shafts for alternately acting upon the different shafts to control their movements.

2. The combination with a suitable support for a sheet of metal and a plunger arranged to operate on the sheet, of a clamping-jaw for holding the metal in position while it is being operated upon, toggle-levers for advancing and retracting the jaw, rock-shafts for operating the toggle-levers, master-wheels at the opposite ends of the shafts, each wheel being provided with a cam arranged to alternately act upon the different shafts and means for operating the master-wheels.

3. The combination with a suitable sup-

port for holding a sheet of metal to be operated upon and a plunger arranged to operate upon the metal, of a clamping-jaw for holding the metal in position while being operated upon toggle-levers for advancing and retracting the jaw, rock-shafts for operating the toggle-levers, cranks on the opposite ends of each shaft and cams located at the opposite ends of the shafts, each cam being arranged to operate alternately on the cranks of the different shafts at the end where it is located.

4. The combination with suitable means for supporting and operating on a sheet of metal, of a clamping-jaw for holding the metal in position while being operated upon, rock-shafts connected with the clamping-jaw for lowering it and raising it and cams at the opposite ends of the rock-shafts, each of said cams being arranged to alternately operate one rock-shaft in a direction to depress the jaw and the other rock-shaft in a direction to lift the jaw.

5. The combination with suitable means for supporting a sheet of metal in position to be operated upon and means for operating on the metal, of a clamping-jaw for holding the metal in position while it is being operated upon, rock-shafts connected with the clamping-jaw for lowering it and raising it and cams at the opposite ends of the rock-shafts to simultaneously rock the shafts in opposite directions.

6. The combination with suitable means for supporting a sheet of metal in position to be operated upon and means for operating on the sheet of metal, of a clamping-jaw movable toward and away from the sheet of metal, toggle-levers for operating the jaw, rock-shafts for operating the toggle-levers, cams at the opposite ends of the shafts for operating the shafts and means for securing the toggle-levers to the clamping-jaw in vertical adjustment.

In testimony that I claim the foregoing as my invention I have signed my name, in presence of two witnesses, this 13th day of February, 1906.

PAUL R. HAHNEMANN.
